UNITED STATES PATENT OFFICE.

EDGAR GARDNER CALKINS, OF MORLAND, KANSAS.

EGG TRAY.

Application filed April 27, 1926. Serial No. 104,940.

This invention relates to an improved egg tray of the type wherein provision is made to automatically turn the eggs over and over at predetermined periods of time to facilitate hatching in an incubator.

Briefly, the invention comprises an appropriate metal tray equipped with a plurality of egg supporting rollers spaced properly to receive a multiplicity of eggs in a well known manner. Disposed over this series of rollers is a rotary shaft which is manually operated, and this shaft has operating connection with the rollers thru the medium of means which constitutes the novelty of this invention.

My object is to generally improve upon inventions of this nature by providing a structure which is believed to be a decided improvement on similar known devices in that it is more simple in construction, positive in operation, and easily repaired.

Other objects and advantages of the invention will become apparent from the following description and drawings.

In the accompanying drawings forming a part of this application and in which like numerals are employed to designate like parts throughout the same:

Fig. 1 is a top plan view of a tray constructed in accordance with the invention.

Fig. 2 is a section taken on the line 2—2 of Fig. 1.

Fig. 3 is a longitudinal section taken on the plane of the line 3—3 of Fig. 1.

Fig. 4 is a fragmentary perspective view.

Referring to the drawings in detail, the reference character 1 designates the tray proper. This is of light weight sheet metal, being of general rectangular form, and the side members being of right angular cross-section. Rotatably mounted on the vertical walls of the tray in the manner shown are the egg supporting rollers. These may be of wood and the pivots may be of any preferred form. Also, they are spaced in parallelism at suitable distances to properly support the eggs. The manner of placement of the eggs is well known and is, therefore, not shown in the drawings. It may be added, however, that the rollers are disposed at an elevation in the tray to prevent easy loss when handling the tray.

The rotary shaft is designated by the nu-

meral 3 and it will be seen that it is mounted for rotation in suitable bearings formed in the end walls of the tray. By preference, it is arranged at the center of the tray and is spaced above the central portions of the rollers. It will be noticed that one end of the shaft projects beyond the tray and is constructed to accommodate a removable hand crank 4 which is employed to turn the shaft in opposite directions. The means employed for imparting rotation to the rollers comprises a plurality of flexible elements 5, there being one for each roller. One end of each cord or element is connected as at 6 to the shaft over the proper roller, and the other end is attached to the shaft as at 7. Then too, the intermediate portion of this cord is wrapped or coiled about the roller as indicated at 8. It will also be noted that one end portion of the cord is wrapped around the shaft as plainly shown in Fig. 4.

With the arrangement shown and described, it will be seen that by placing the crank in place and turning the shaft, the rollers will be simultaneously rotated one half-turn. For instance, when the cords are in the position shown in Fig. 4, and the shaft is turned in a direction from left to right, the end of the cord which is then wrapped will unwrap and the other end will wrap. Obviously, this operation will rotate the roller beneath it. As all of the cords act in the same manner, all of the rollers will be automatically turned and the eggs will turn to change their positions. In this manner the eggs can be turned from time to time to accomplish the desired result.

It is believed that by considering the drawings in connection with the description, a clear understanding of the invention will be had. For this reason, a more detailed explanation is deemed unnecessary.

Minor changes coming within the invention as claimed may be resorted to without departing from the spirit of the invention.

I claim:

An egg turner comprising a tray, a plurality of egg supporting rollers mounted for rotation in said tray and disposed in spaced parallelism and in the same plane with each other to receive the eggs, a single shaft mounted for rotation in the tray over

the rollers, said shaft being disposed over the central portions of the rollers, means for rotating the shaft, and means for simultaneously turning all of the rollers, said means comprising a plurality of flexible elements, there being one for each roller and the ends of said element being attached to

the shaft and the intermediate portion being wrapped around the complementary roller.

10

In testimony whereof I hereunto affix my signature.

EDGAR GARDNER CALKINS.
